OTHER PUBLICATIONS

Photos 1, 2 and 3 show typical wall facings formed of concrete which can be purchased from local building supply stores. These facings are approximately 1-2 inches thick and provide a "layered" appearance. These facings are not wall blocks but are applied to single block walls for decorative purposes.

U.S. Appl. No. 10/640,485, filed Aug. 13, 2003, M. Todd Evans.

U.S. Appl. No. 29/188,184, filed Aug. 13, 2003, M. Todd Evans.
